UNITED STATES PATENT OFFICE.

EDWARD C. MANGIN, OF COLORADO SPRINGS, COLORADO.

MINER'S LAMP.

1,037,948.

Specification of Letters Patent. Patented Sept. 10, 1912.

Application filed March 28, 1912. Serial No. 686,924.

To all whom it may concern:

Be it known that I, EDWARD C. MANGIN, a citizen of the United States, residing at Colorado Springs, in the county of El Paso and State of Colorado, have invented certain new and useful Improvements in Miners' Lamps, of which the following is a specification, reference being had to the accompanying drawings.

10 This invention relates to new and useful improvements in miners' lamps and has for its object to provide a device of this character which will be simple, strong, and exceedingly convenient to handle.

15 Another object of the invention is to provide a lamp of this character which will possess advantages in points of efficiency and durability, is inexpensive of manufacture and at the same time is simple in construction and operation.

With the above and other objects in view the invention consists in the novel features of construction and in the arrangement and combination of parts hereinafter more fully 25 described, pointed out in the claims, and shown in the accompanying drawings, in which,

Figure 1 is a side elevation of a miner's lamp constructed in accordance with my invention; Fig. 2 is a longitudinal sectional view; and Fig. 3 is a sectional view on the line 3—3 of Fig. 1.

Referring more particularly to the drawings, 1 indicates a tubular body member having one of its ends open and provided with the internal screw threads 2. This body member is adapted to serve as a supply reservoir to contain the oil, gasolene, wood alcohol, or other illuminating material which 35 may be used. The material is introduced into the body through the tubular extension 3 formed integral with the body at one side thereof, said tubular extension having its outer end provided with the screw threads 40 4, upon which a threaded cap 5 is secured to prevent any leakage of the material after the reservoir has been filled.

A cylindrical plug 6 is provided having external screw threads 7 formed thereon and 50 adapted to be threaded in the open end of the body 1. This plug is provided at one end with a tapering portion 8, and having a threaded reduced portion 9 formed on its outer end. The plug 6 is provided with the 55 centrally arranged opening 10 in which is arranged the wick tube 11, said tube extend-

ing into the body 1 and is adapted for frictional engagement with the wall of the opening 10 to hold the same in position. A wick 12 is arranged within the tube 11 and having 60 its inner end extending beyond the end of the tube so as to absorb the illuminating material from the body member, the outer end of the wick extending slightly beyond the outer end of the tube so that it can be 65 quickly and easily ignited.

A tubular regulating sleeve 13 is provided having internal screw threads formed at one end thereof and adapted to engage with the threaded reduced portion 9 so that the same 70 may be adjusted to regulate the size of the flame. A tubular member 14 is arranged within the sleeve 13 and spaced from the wall, said tubular member being adapted to be slidably mounted upon the upper end of 75 the wick tube 11. The space between the sleeve 13 and the tubular member 14 is closed at the outer end of the sleeve 13 as shown at 15 so as to prevent any leakage of the illuminating material at this point. 80

A tubular cap 16 is provided and adapted to be arranged over the tubular sleeve 13 and to inclose the outer end of the wick when the same is not in use so that the lamp may be easily carried about in the pocket. 85 To prevent accidental loss of this cap the same is attached by means of the chain 17 to the body portion of the lamp.

From the above description taken in connection with the drawings the use, advantages, and operation of my improved miner's lamp will be readily understood. 90

While I have shown and described the preferred form of my invention it will be obvious that various changes in the details 95 of construction and proportions may be resorted to for successfully carrying my invention into practice without sacrificing any of the novel features or departing from the scope thereof.

What I claim is:—

1. In a device of the character described, the combination of a tubular body member, having an open end provided with internal screw threads, an externally threaded plug 105 adapted to be screwed into the open end of the body member, a tapering portion formed on said plug, having a reduced threaded end, said plug being provided with a centrally arranged opening, a wick tube disposed within said opening, a regulating sleeve threaded on the reduced end of the 110

tapering portion and adapted for adjustment to regulate the size of the flame, a tubular member disposed within said sleeve and arranged in spaced relation with the 5 walls thereof, said tubular member being secured to the sleeve at the outer end thereof whereby the space between the tubular member and the sleeve will be closed to prevent any leakage of the illuminating material at 10 this point.

2. In a device of the character described, the combination of a tubular body member, having an open end provided with internal screw threads, an externally threaded plug 15 adapted to be screwed into the open end of the body, a tapering portion formed on the outer end of said plug, having a reduced threaded end, said plug being provided with a centrally arranged opening, a wick tube 20 disposed in said opening and adapted to frictionally engage the wall thereof to hold

said tube in position, a wick arranged within said tube, a regulating sleeve provided with internal screw threads and adapted to be screwed on to said threaded reduced portion, said sleeve being adapted for adjustment to regulate the size of the flame, a tubular member disposed within said sleeve and arranged in spaced relation with the walls thereof, said tubular member being 25 secured to the sleeve at the outer end thereof whereby the space between the tubular member and the sleeve will be closed to prevent any leakage of the illuminating material at 30 this point.

35 In testimony whereof I hereunto affix my signature in the presence of two witnesses.

EDWARD C. MANGIN.
